UNITED STATES PATENT OFFICE

2,503,492

STATIONARY AWNING

Henry G. Jones, Austin, Tex.

Application January 7, 1947, Serial No. 720,634

1 Claim. (Cl. 20—57.5)

1

This invention relates to awnings and more particularly to metal or fixed awnings having fixed openings or louvres.

It is an object of this invention to provide an improved awning of the kind to be more specifically described hereinafter, which may be readily disassembled for shipping or storing and which may be readily assembled where it is to be used. The construction of the awning is such that there are provided a front and side members as a unit which may be quickly and easily assembled together and fixed in a prefabricated frame which may be fixed on the building.

Another object of this invention is to provide a metal awning of this kind which is so constructed and arranged as to be about fifty percent (50%) lightproof from outside and which is approximately ninety-five percent (95%) rainproof.

Still another object of this invention is to provide an improved awning of this kind which may be made of a light metal as aluminum which is constructed with pre-finished separate panels to provide for ready and economical shipping in a flat container to conserve shipping space and to provide for the lessening of the possibility of damage in transit.

Yet another object of this invention is to provide an improved awning of this type which may be assembled by persons unskilled in such work in a ready and efficient manner.

With the above and other objects in view, my invention consists in the arrangement, combination and details of construction disclosed in the drawings and specification, and then more particularly pointed out in the appended claim.

In the drawings,

Figure 1 is a front elevation of a metal awning constructed according to an embodiment of this invention,

Figure 2 is a side elevation,

Figure 3 is a fragmentary vertical section taken on the line 3—3 of Figure 2,

Figure 4 is a fragmentary section taken on the line 4—4 of Figure 3,

Figure 5 is a fragmentary detail section taken on the line 5—5 of Figure 1,

Figure 6 is a fragmentary detail section taken on the line 6—6 of Figure 2,

Figure 7 is a detail section taken on the line 7—7 of Figure 2,

Figure 8 is a transverse section taken on the line 8—8 of Figure 2,

Figure 9 is a fragmentary section taken on the line 9—9 of Figure 1,

2

Figure 10 is a detail section taken on the line 10—10 of Figure 2.

Referring to the drawings, the numeral 15 designates generally a metal awning of the type having fixed louvres on the front and sides thereof, which is so contructed that the front panel 16 and the side panels 17 may be constructed as a unit and readily assembled on the job and may be shipped in a knocked-down condition.

The front panel section 16 and the side panels 17 are adapted to be fitted at the time of assembly into a base frame 18 which is adapted to be fixed to a wall or other suitable structure about a window opening or the like. The base frame 18 is formed with a pair of L-shaped side members 18a. The L-shaped side members 18a are formed with a vertical channeled member 19 and a horizontal channel member 20, fixed at the lower end of the vertical member 19. The vertical member 19 is adapted to be fixed to the wall or supporting member with the bight 21 thereof abutting the flat surface of the wall and the arms 22 extending outwardly therefrom.

The bight 24 of the horizontal member 20 is disposed downwardly with the arms 25 thereof extending upwardly. A U-shaped horizontal member 26 is fixed between the L-shaped side members 18a at the outer end of the arms 20. The transverse member 26 is substantially U-shaped in configuration, having the bight 27 thereof extending outwardly of the frame 18 and having a vertically extending flange 28 fixed to or formed on the inner edge of the upper arm 29 thereof. The side panels 17 are formed with peripheral frame members 30. The frame 30 is substantially triangular-shaped in outline and the frame members are Z-shaped in cross section, having a central web 31 and oppositely disposed flanges 32 on the opposed side edges of the web 31.

Two of the frame members 30 of the side panels are disposed in right angularly related position and the third frame member is inclined between the free outer ends thereof. Louvres 34 are fixed to the inwardly extending flanges 32 on the inner side of the frame members 30. The louvres 34 are inclined downwardly and outwardly with the lower end of each louvre disposed outwardly of and overlapping in spaced relation the upper fixed end of the louvre directly below it.

The lower frame member 30 of the side panel 17 is adapted to overlie the outer upwardly extending arm of the base frame 18 and is adapted to be fixed thereto by bolts 35 or other suitable attaching means. The bolts 35, for quick assembly of this unit, may be of the self-tapping type which

are easily inserted for holding the assembly in such a manner that it may be readily knocked down.

The Z-shaped frame members 30 along the rear vertical member of the side panel are disposed with one flange 32 extending outwardly and rearwardly and are adapted to overlie the arm 22 of one of the vertical U-shaped base frame members. Both of the side panels 17 are constructed in the same manner so that the description of one will fit the description of the other.

The front panel 16 is formed of a frame, having horizontal Z-shaped members 36 and vertical U-shaped members 37 having a flange 38 fixed to the inner arm 39 of the U-shaped frame member 37. Louvres 40 are fixed between the inclined side frame members 31, being fixed at their ends to the upper side of the flange 38. The downwardly extending flange 41 of the lower Z-shaped front panel frame member 36 is adapted to overlie the bight 21 of the horizontal U-shaped member 26 and may be fixed thereto by self-tapping screws 35 as above described.

The upper end of the front panel 16 merely abuts the vertical members of the base frame 18 and is only secured thereto by a transverse cover plate 42. The cover plate 42 is substantially U-shaped in cross section, having one arm thereof fixed to the bight of the vertical members 19, and the other arm fixed to the upper flange 43 of the upper Z-shaped frame member 36 of the front panel frame. By this construction a substantially triangular opening remains at the corner formed by the junction of the front panel 16 with the upper end of the base frame 18. For sealing this opening, an end cap 44 is provided, which is substantially U-shaped, having both arms fitting underneath the arms of the cover 42 and having the bight 45 thereof covering the opening thus left. The end cap 44 is disposed then at right angles to the cover 42.

By a construction of this kind, the base frame 18 may be first constructed or prefabricated and fixed to the opening about a window. The side panel members 17 are then put in place and the flanges of the edges of the side panel which abut the edges of the base frame are fixed thereto by screws or other suitable fastening devices. When the side panels 17 are fixed in place on the base frame 18, the front panel 16 may be set in place with its lower edge engaging the outer horizontal member of the base frame and the side edges engaging the inclined upper outer edge of the side members.

The transverse cover plate 42 when fixed in place by screws as 35 and the end caps 44, complete the erection of this metal awning. The louvres 40 of the front panel 16 are formed substantially the same as the louvres 34 of the side panels with the addition of a downwardly bent

outer terminal portion 47 overlying the upper end of the lower louvre. A construction of this kind provides a metal awning which has substantially fifty percent outside vision and is approximately ninety-five percent rainproof.

I do not mean to confine myself to the exact details of construction herein disclosed, but claim all variations falling within the purview of the appended claim.

What I claim is:

An improved metal awning comprising a frame including a pair of L-shaped side members, the vertical leg of each of said members being U-shaped in cross-section with the side flanges thereof extending forwardly and the connecting web adapted to be disposed against a supporting structure for attachment thereto, the horizontal leg of each of said members being U-shaped in cross-section, a horizontal rearwardly opening channel connecting member extending between the outer ends of said horizontal legs, said connecting member being formed with an upstanding flange along the rear edge of the upper portion thereof, a pair of side panels each including a triangular panel frame having vertical, horizontal, and diagonal peripheral members, each including a connecting web and oppositely extending flanges formed along the inner and outer edges of said latter web, the outer flanges of the horizontal and vertical peripheral members being adapted to overlie the outer flanges of said horizontal and vertical legs of said L-shaped side members, horizontally extending side louvres secured between said vertical and diagonal peripheral members, a front panel including a frame having upper and lower peripheral members of Z-shaped cross-section, and rearwardly opening U-shaped side peripheral members, horizontally extending louvres secured between said side peripheral members, the outer legs of said side peripheral members overlying the outer flange of said diagonal peripheral member, the outer leg of said lower peripheral member overlying the web of said horizontal connecting member, a substantially U-shaped cover member engaging over the top ends of said vertical legs of said frame side members and said upper peripheral member, and fastening means extending through said overlying flanges, legs and webs for securing said side panels and said front panel on said frame and to each other.

HENRY G. JONES.
